UNITED STATES PATENT OFFICE.

LEONARD E. WATSON, OF ST. MARYS, WEST VIRGINIA.

BRAKE-BAND TOOL.

Application filed January 22, 1926. Serial No. 83,102.

This invention relates to means for facilitating the renewal of the transmission bands in the Ford type of motor vehicle, the general object of the invention being to provide means for drawing a band around its drum.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Fig. 1 is a sectional view through a transmission means showing a spring member being used to place a band on its drum.

Fig. 2 is a similar view showing another step in the operation.

Fig. 3 is a view of the spring member.

Fig. 4 is a partial view of the band.

Fig. 5 is a view of the detachable ear therefor.

As is well known, the Ford type of motor includes in its transmission the drums 1 and 2, each band having a detachable ear 3 which has key-hole shaped slots 4 therein for engaging the headed studs 5 on the band and a round hole 6 for receiving a rivet 7 on the band. This end of each band is also provided with a hole 8.

When a band is to be removed, this ear is removed and then the other ear seized and the band pulled from around the drum. In replacing the band or a new one, the end thereof which carries the detachable ear is inserted between the transmission casing and the drum, after the upper part of the case has been removed, and a tool must be used to "fish" for the band if the band fails to be guided by the flanges of the drum as it is being pushed into place. It is also difficult to place the detachable ear on the band and to remove it therefrom and to hold the band tight on the drum when the nut and washer are being placed on the shaft.

I have provided means for facilitating the different steps in the operation of removing and replacing bands. The invention comprises a spring strip B. The strip is of spring metal and has a tab 9 pivoted to one end, said tab having a keyhole shaped slot

10 which is adapted to engage one of the headed studs 5 of the band. The other end of the strip B is bent upon itself, as shown at 11.

When a band is to be removed, the nut and washers are taken off the shaft and the shaft removed and then the ear is removed from the band by a suitable tool. The band is then seized by its other ear and pulled from around the drum. The tab 9 of the member B is then connected with the new band or the old one if this is to be replaced, by placing the slot 10 over one of the headed studs 5 of the band. The end 11 of the spring strip B is then placed on the drum and the strip pushed upon to cause it to pass around the drum as shown in Figure 1. The strip is then pulled around the drum, and as the band is attached thereto, the band will also be pulled around the drum, as shown in Figure 2. The band is pulled around the drum until its permanent ear engages the drum and a part of the casing, when further movement will be prevented. This will bring the other end of the band at the top of the drum. The tab 9 is moved to one side so as to expose the opening 8 and then a tool is placed in said opening. The tab is then removed from the band and the ear 3 placed over the studs 5.

From the foregoing, it will be seen that I have provided simple means whereby the transmission bands can be easily removed from and replaced on the drums through the inspection opening and without removing the upper portion of the transmission case. As will be seen from the drawings, by making the band or strip B of spring metal, its tension will cause it to coil upon itself and thus it will follow the contour of the drum as it is pushed over the same so that there is no danger of the band being checked in its movement from any part of the transmission casing.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A tool for facilitating the removal of a transmission band from a transmission drum comprising a strip or band formed of

spring metal and means at one end of the band for detachably engaging a part of a transmission band to connect the said transmission band to the tool, the tension of the 5 spring strip causing it to follow the contour of the drum as the strip is pushed over the drum.

2. A tool for facilitating the removal of a brake band from a transmission drum comprising a spring strip and a tab hinged to one end thereof so that it can move about an axis which is at right angles to the length of the strip and said tab having a slot therein, the tension of the spring strip causing it 15 to follow the contour of the drum as the strip is pushed over the drum.

3. In a transmission band installer of the class described, a predetermined length of normally coiled flexible material adapted for 20 forcible engagement around a drum of the transmission, one end of said length of material being adapted for detachable connection to one end of the transmission band being installed, the other end of the length of material 25 providing a means whereby the same may be moved around the drum for positioning the transmission band on the drum, the length of the material being removed from the band when the latter is in its proper position.

4. In a transmission band installer of the class described, an elongated strip of normally coiled spring metal adapted for forcible engagement around the drum of the transmission, a hook at one end of said strip 35 adapted for detachable engagement with one end of the transmission band, the other end of the strip providing a handle portion whereby the strip may be moved around the 40 drum for positioning the transmission band thereon, said hook being disengaged from

the transmission band when the latter is in proper position.

5. In a transmission band installer of the class described, an elongated strip of normally coiled spring metal adapted for forcible engagement around the drum of the transmission, a plate attached to one end of the strip, a hook formed on the outwardly projecting end of the plate and adapted for 45 detachable engagement with one end of the transmission band, the other end of the strip providing a handle portion whereby the strip may be moved around the drum for positioning the transmission band thereon, 55 said hook being disengaged from the transmission band when the latter is in proper position around the drum.

6. A tool for inserting a band around a transmission drum on an automobile, comprising a resilient member of less curvature than the curvature of the drum, and provided at one end with means adapted for 60 detachable connection with one end of the band.

7. A tool for inserting a band around a transmission drum of an automobile, comprising a resilient member of less curvature than the curvature of the drum, and provided at one end with a slot for detachably 70 connecting with one end of the band.

8. A tool for inserting a band around a transmission drum of an automobile, comprising a resilient member of less curvature than the curvature of the drum and of substantially the width of the band, and provided at one end with manual gripping means and at the other end with a slot for detachably 75 connecting with one end of the band.

In testimony whereof I affix my signature.

LEONARD E. WATSON.
